Primary Examiner — Leanne Was-Englehart*(74) Attorney, Agent, or Firm* — Edwin H. Crabtree; Ramon L. Pizarro(57) **CLAIM**

An ornamental design for a corner shield, as shown in the drawings and described in the specifications.

DESCRIPTION

FIG. 1 is a front perspective view of the invention;

FIG. 2 is a rear perspective view of the invention, shown in FIG. 1;

FIG. 3 is a side elevation view of the invention, shown in FIG. 1 and an opposite side elevation view would be a mirror image of FIG. 3;

FIG. 4 is a rear elevation view of the invention, shown in FIG. 1;

FIG. 5 is a top plan view of the invention, as shown in FIG. 1; and,

FIG. 6 is a bottom plan view of the invention, as shown in FIG. 1.

The broken lines in the drawings depict portions of the corner shield that form no part of the claimed design.

1 Claim, 5 Drawing Sheets(56)
